UNITED STATES PATENT OFFICE.

VIVIAN M. SWANN, OF BROOKLYN, NEW YORK.

CARPENTER'S HATCHET.

Application filed August 24, 1922. Serial No. 523,948.

To all whom it may concern:

Be it known that I, VIVIAN M. SWANN, a citizen of the United States, residing at New York city, borough of Brooklyn, in the 5 county of Kings and State of New York, have invented certain new and useful Improvements in Carpenters' Hatchets, of which the following is a specification.

This invention relates to mechanics' tools 10 and has particular reference to hatchets of the general class commonly used by shinglers or lathers in which the top of the tool is so reduced or cut away as to facilitate the use of the hammer end or poll thereof close to a 15 wall or corner.

Among the principal objects of the invention is to provide a hatchet having improved nail pulling facilities, the features pertaining to the nail pulling being so constructed as to be well shrouded, rendering it practically impossible for the nail slot or notch to become engaged with the operator's clothing or any other outside condition that might interfere with the use of the 20 tool or tend to cause an injury to any person, and at the same time to provide maximum strength and durability not only for the pulling of the nails but making for the durability of the tool itself.

Another object of the invention is to provide an improved type of carpenter's hatchet having nail pulling facilities located along the top edge thereof and so designed that the maximum strength of the handle for nail 25 pulling purposes will be subserved, the strain for this purpose being brought within the plane of the widest dimension of the handle.

A still further object of the invention is 30 to provide a tool of the character stated which is not only neat in appearance but which is particularly well adapted for a well balanced swing in either the driving of nails or the cutting of material with the 35 use of the blade.

With the foregoing and other objects in view the invention consists in the arrangement and combination of parts hereinafter described and claimed, and while the invention 40 is not restricted to the exact details of construction disclosed or suggested herein, still for the purpose of illustrating a practical embodiment thereof reference is had

to the accompanying drawings, in which like reference characters designate the same 55 parts in the several views, and in which—

Figure 1 is a perspective view of a hatchet made in accordance with this invention, a portion of the handle being broken away.

Fig. 2 is a side elevation of the same, one 60 face of the hatchet being broken away to better disclose the construction.

Fig. 3 is an elevation of the top edge of the hatchet.

Referring now more specifically to the 65 drawings I show my improved hatchet as comprising a head or poll 10, the face 11 of which may be of any suitable form or contour for nail driving or like purposes, a blade 12 of any suitable design and properly sharpened, and intermediate the blade and the head is arranged the handle socket 13 as usual of any suitable construction per 70 se, not differing essentially from the features of other makes of tools. The handle 75 14 is fitted into the socket 13 and suitably wedged therein as usual at 15.

Instead of forming a nail pulling claw or notch at the bottom of the poll or along the bottom edge of the blade as heretofore, 80 which features are always liable to cause interference with outside conditions as well as likelihood of breakage of the handle when the strain thereon is transverse to the plane of the blade, I form the top edge portion 85 of the hatchet with a peculiarly arranged socket or recess 16, the same being arranged opposite the handle and extending entirely across the same both longitudinally of the hatchet and transversely thereof. In the formation of this socket there is observed an open slot 17 which widens or flares both laterally and longitudinally toward the handle socket 13, the ends of the slot at 90 18 and 19, proximate to the poll and the 95 blade respectively, being of acute angular form for the secure engagement of the nail head or shank, the head of the nail being engageable in the under cut adjacent portion of the slot or recess 18' or 19'.

It is to be particularly noted that the walls bounding the slot 17 are in effect continuous ribs 20 extending all the way from the blade to the poll, whereby not only maximum strength in the implement is observed but the ribs constitute shrouding 100 105

means or guards for the wedge end of the handle and the nail pulling features making a smooth symmetrical and well balanced implement.

5 The end of the handle is introduced into the socket 13 in the usual way and the wedge or wedges are introduced to secure the same therein. The free open slot 17 does not interfere with the insertion of the wedges, and 10 any projecting portion of either the handle or the wedges within the cavity 16 may be trimmed off by the use of a chisel or other tool through either of two similarly formed and arranged side wall slots 21.

15 The top portion of the poll is rounded off somewhat at 22, among the purposes for which are to facilitate the grasping of the nail head in the claw 18 and also to give a more powerful fulcrum for the claw 18 20 when the tool is swung around said rounded top in the direction of the arrow 1, Fig. 2. It is well understood that the initial pull or starting of the nail is the most difficult, requiring the greatest mechanical advantage 25 in the use of the handle as a lever, and this rounded effect of the tool furnishes immediately this advantage. After the nail has been started the continued or final pull thereon may be accomplished by simply 30 shifting the tool endwise and the nail head along and within the open slot 17, bringing the nail head into the claw 19, and the pull being completed, swinging the tool around the point 23 of the blade as a fulcrum as suggested by the arrow 2. At this time the nail having been started from its set position it will require less force and the fulcrum end of the tool accordingly will be 35 longer than as first stated.

40 I claim:

1. In a hatchet, a nail pulling device arranged along the top edge thereof and including a claw formed adjacent to the poll, said claw being constituted by an under cut 45 recess extending downward toward the poll and utilized for starting the nail, the side walls of the claw being continuous spaced ribs merging into the blade of the hatchet and forming an auxiliary claw operative

around the point of the blade for completing the pull of the nail. 50

2. The herein described nail pulling hatchet formed with a recess in its top edge portion opposite and indirect alinement with the end of the handle and including a claw adjacent to the blade and having an undercut formation to receive the head of the nail within the shank portion of the blade for the extraction of the nail while swinging the hatchet around the point of the blade as 55 a fulcrum, the side wall portions of the claw being extended beyond the handle and merged into the poll of the hatchet. 60

3. A nail pulling hatchet, the top edge portion of which is formed with an under 65 cut recess opposite the end of the handle, the side wall portions of which constitute continuous ribs merging into the poll and the blade portions respectively and forming claws at both ends of the recess, there being provided a side wall opening formed adjacent to the end of the handle and below the top slot or opening of the recess for the trimming off of the end of the handle at 70 the bottom of the recess. 75

4. A nail pulling hatchet, the top edge portion of which is formed with an under 80 cut recess opposite the end of the handle, the side wall portions of which constitute continuous ribs merging into the poll and the blade portions respectively, the top portion of the poll being rounded in the direction of the plane of the blade to facilitate the application of the nail pulling claw 85 to the head of a nail for maximum pulling force, while the strain on the handle is brought along the plane aforesaid. 90

5. In a tool of the class set forth, a head having a handle socket, said head being formed remote from the handle socket with 90 a recess for receiving the head of a nail to be drawn, said recess being formed on its opposite ends with claws adapted to receive in succession the nail head while being shifted along the recess from one claw to the other, substantially as described. 95

In testimony whereof I affix my signature.
VIVIAN M. SWANN.
